UNITED STATES PATENT OFFICE.

WILLIAM H. MATTHIES, OF HACKENSACK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,334,311.

Specification of Letters Patent. Patented Mar. 23, 1920.

Application filed December 27, 1916. Serial No. 139,118.

To all whom it may concern:

Be it known that I, WILLIAM H. MATTHIES, a citizen of the United States, residing at Hackensack, in the county of Bergen and State of New Jersey, have invented certain new and useful Improvements in Telephone Systems, of which the following is a full, clear, concise, and exact description.

In telephone systems of the present type, it is customary to locate at each office intercepting positions which receive the intercepted calls which come to that office. It is now proposed to centralize all the intercepted service positions of multi-office systems at one of the offices of this system.

With this centralization of the intercepted service positions, it is necessary to provide means to inform the intercepting operator, upon receiving a call, at which office the call has been intercepted, as well as the character of the intercepted call which the operator is about to answer. It will be understood that the intercepted calls may be transferred at incoming switches or at final switches.

The main feature of this invention is the provision of means to control the operation of automatic switches so that these switches will be set in operative relation to corresponding groups of lines terminating thereat.

Another feature of this invention is the provision of a counting device to control the group selection at the finder switch.

Another feature of this invention is the employment of means to actuate a counting device in accordance with the number of subgroups of lines tested by the finder and means to actuate the complement of this number of relays to control the setting of a second switch on a subgroup of lines corresponding to the subgroup selected by the finder.

In order to bring intercepted calls to intercepted positions, the lines from the incoming or final switches are cross-connected to special lines wired to the terminals of an automatic switch, which is herein termed "an intercepted service finder". The intercepted finder is capable of finding any one of 500 lines which terminate in its fixed contacts. These 500 lines are divided into main groups of 100 lines each, each group

being controlled by one of the five sets of brushes of the finder, and each main group is divided into subgroups of ten lines each. 55 Connected to the intercepted service finder by means of a two wire trunk, is an intercepted service switch or connector, which is located in the same office as the intercepted service positions. 60

The drawings with Figs. 1, 2 and 3, arranged in the order named and with Fig. 4 below Fig. 2, represent a portion of a telephone system employing the present invention. 65

In general, the operation of this system is as follows: Means is provided to select a group at the finder switch, which means also serves to select a corresponding group at an intercepted service connector. As the finder switch is elevated to engage with the calling line, each subgroup of ten lines passed during this elevating operation locks up one pair of relays of a chain of counting relays. After the calling line has been found by the 75 finder switch, the brushes of the connector switch are raised and caused to select a subgroup of ten lines, corresponding to the complement of the subgroup selected by the finder and determined by the number of 80 counting relays of the counting chain locked up during the finding operation. This arrangement causes the connector switch at the distant end of the trunk to bring the call to the attention of an operator over a trunk 85 located in the subgroup of trunks corresponding to the subgroup to which the calling line was connected.

When a calling subscriber initiates a call to a line which has been cross-connected to 90 a line leading to the centralized intercepted service position, automatic switches, whose brushes are indicated at 101, 102 and 103, operate to connect this calling substation to the link circuit terminating at the intercepted service finder. As soon as this connection has been established, relay 104 is energized over a circuit extending from grounded battery, winding of relay 104, armature and back contact of relay 105, 100 conductor 106, the upper brush of set 103, conductor 110, upper brush of set 102, to ground. The line relay 104 attracts its armatures and thereby completes an energiz-

ing circuit for the differentially wound relay 107. This circuit may be traced from ground, armature and front contact of relay 104, left-hand winding of relay 107, 5 resistance 108, front contact and left-hand armature of relay 104, to grounded battery. It might here be noted that the relay 107 is common to the lines of a particular group, and as soon as relay 107 is energized at its 10 armature it will remove battery from the test wire of this calling group and close battery to the common starting wire of this group.

An allotter is associated with the intercepted service finder system so that only one 15 of the finders employed is in a position to start searching for a call at any one time. As is usual in allotting systems of this type, the sequence switch 200 associated with the 20 allotter is moved from position 18 into position 1, when this allotter is allotted for use. Each allotter has associated with its controlling sequence switch a secondary sequence switch 400, which operates 25 to connect the allotter with an idle sender. When the allotter sequence switch 200 reaches position 1, its secondary sequence switch 400 will be in such a position that one of three idle senders will be associated with 30 the allotter.

Assuming that an idle sender has been connected to the allotter switch, the relay 201 will be energized over a circuit extending from ground, right-hand armature and 35 back contact of relay 423, contact 452 winding of relay 201, conductor 206, contact 207, over the common starter wire 208, front contact and armature of 107, to grounded battery. Relay 201 is energized and 40 attracts its armatures, and at its right-hand armatures completes a circuit to move sequence switch 200 out of position 1, which circuit extends from grounded battery, magnet of sequence switch 200, conductor 209, contact 210, front contact and right-hand armature of relay 201, conductors 211 and 45 212, contact 213, to ground. Relay 201 will remain energized over a circuit extending from grounded left-hand armature and back contact of relay 202, conductors 203 and 204, contact 205, winding of relay 201, contact 214, contact 215, resistance, front contact and left-hand armature of 50 relay 201, conductor 216, contact 217, contact 218, conductor 219, contact 401, to grounded battery. As soon as sequence 55 switch 200 arrives in position 2, a circuit is completed for operating sequence switch 400. This circuit extends from grounded 60 battery, magnet of sequence switch 400, conductor 402, contacts 220 and 221, conductor 222, front contact and right-hand armature of relay 201, conductor 211, conductor 212, contact 213, to ground. The sequence 65 switch 400 will continue to rotate as long as

the relay 201 remains energized. As the sequence switch 400 rotates into its successive positions, one of the contacts 403, 447, 448, 449 or 450 maintains the holding circuit of relay 201 over one of the test conductors 70 similar to 404 common to a group of trunks, to grounded battery at relay 107. The contacts 403, 447, 448, 449 and 450 are so arranged that the closure of the test wire of the next succeeding group is effected before the opening of the circuit to the test wire of the group being tested. The sequence switch 400 continues to rotate until 75 it transfers the circuit of the relay 201 to a test circuit similar to 404 of the calling 80 group, which test circuit will be opened, due to the energized condition of the relay 107, as previously described. The relay 201 will therefore deenergize and complete a circuit for moving the sequence switch 85 200 out of position 2, which circuit is established from grounded battery, magnet of sequence switch 200, conductors 236 and 209, contact 223, back contact and right-hand armature of relay 201, conductor 211, conductor 212, contact 213 to ground. As the sequence switch 201 moves out of position 2, it 90 interrupts at the contacts 220 and 221 the operating circuit of the sequence switch 400, as previously described. 95

As soon as the sequence switch 200 reaches position 3, a circuit is closed from grounded battery, left-hand armature and back contact of relay 224, resistance 225, contacts 226 and 227, conductor 228, through one of 100 the contacts similar to 405 over the differential release wire 406, right-hand winding of relay 107, front contact and right-hand armature of relay 104, to ground. The resistance 225 associated with the allotter circuit and the resistance 108 of the line circuit have the same value, so that the differential relay 107 will become deenergized. This will remove battery from the common 105 starter wire at the front contact and armature of relay 107 and will apply it to the test wire of this group. If, however, there are two or more simultaneous calls originated in this subgroup of 100 lines, then the relay 107 will only become deenergized 110 when the number of resistances 225 in the circuits of the intercepted service finders are equal to the number of resistances similar to 108, so that as many finders will start as there are calling lines in the group. 115

Also in position 3 of the sequence switch 200 a fundamental circuit is established for brush selection, which circuit may be traced from grounded battery, winding of line relay 202, contact 229, contact 230, resistance 125 231, conductor 232, contact 407, stepping relay 408, armature and back contact of the upper zero counting relay 409, conductor 410, contact 411, conductor 412, contact 233 to ground. Relay 202 and the stepping re- 130

lay 408 will be energized. As soon as the relay 202 is energized, it closes a circuit from ground through its left-hand armature and front contact, conductor 234, contact 235, conductor 236, sequence switch 200 to grounded battery, to move the sequence switch out of position 3.

In this position of the sequence switch, the fundamental circuit, as described, is maintained closed, but the line relay is locked up through its right-hand front contact and armature, conductor 237, contact 230, over the fundamental circuit described. In position 4 of sequence switch 200, an operating circuit for the high-speed up-drive magnet 239 is also completed. This circuit extends from grounded battery, winding of magnet 239, conductor 240, contact 241, conductor 234, left-hand front contact and 20 armature of relay 202, to ground. As the finder switch brush rod is elevated, a circuit in shunt of the fundamental circuit described is established from grounded battery, winding of relay 202, right-hand front 25 contact and armature of relay 202, conductor 237, contact 244, conductor 245, conducting portion of commutator 242, and commutator brush 243, to ground whenever the brush 243 engages a conducting segment. 30 Each time that this shunt circuit is completed as brush 243 encounters a conducting segment of commutator 242, the stepping relay will be short-circuited and will interrupt at its armature and front contact the 35 circuit extending from ground through contact 413, conductor 414, contacts 246 and 247, conductor 248, through one of the contacts 415, 416, 417 or 418, depending on the 40 position at which the switch 400 was brought to rest, through the winding of one of the counting relays, conductor 419, to grounded battery. After the finder switch has taken the number of steps equal to the 45 number of counting relays actuated as determined by the position of sequence switch 400, the relay 202 will become deenergized when the upper zero counting relay 409 attracts its armature. When the relay 202 deenergizes, a circuit is completed for moving 50 sequence switch 200 out of position 4 into position 6, which circuit may be traced from grounded battery at magnet of sequence switch 200, conductor 236, conductor 209, contact 249, conductor 203, back contact and 55 left-hand armature of relay 202 to ground.

When the sequence switch 200 moves out of position 4, ground is removed from the circuit of the counting relays at contact 295.

When the sequence switch 200 reached 60 position 3, a circuit was closed for the allotter 420, which circuit extends from grounded battery, magnet of the sequence switch 420, conductor 421, contact 246, conductor 247, contact 422, to ground. The 65 allotter will then move into its next allot-

ting position to move the next finder from position 18 to position 1. Also in position 3 of sequence switch 200 a circuit is closed from grounded battery, winding of busy relay 423, conductor 424, contact 425, conductor 426, contact 248, to ground, to energize the busy relay of the sender circuit, thus making this sender test busy to the secondary alloters at other finders.

When sequence switch 200 reaches position 6, the fundamental circuit extending to the connector switch is completed. This circuit may be traced from grounded battery, winding of line relay 305, contacts 304 and 303, conductors 302, 253, contacts 252 and 80 251, conductor 232, contact 407, winding of stepping relay 408, armature and back contact of relay 409, conductor 410, contact 411, conductor 412, contacts 249 and 250, conductors 273, 254 and 306, contact 307, to ground. The line relay 305 is energized and establishes a locking circuit for itself through its front contact and left-hand armature, contact 308 over the circuit previously described. As soon as the line relay 90 305 attracted its armatures, a circuit was completed for moving the sequence switch 300 out of position 1, which circuit extends from grounded battery, winding of sequence switch 300, contact 309, right-hand front contact and armature of relay 305, to ground. In position 2 of the sequence switch 300, an energizing circuit for the high-speed up-drive magnet 310 is established from grounded battery, winding of magnet 310, contacts 311, 312, conductor 314, right-hand front contact and armature of relay 305 to ground. A circuit in shunt of the fundamental circuit extends from grounded battery, winding of relay 305, 100 left-hand front contact and armature of this relay, contact 308, conductor 315, contact 316, commutator 317, commutator brush 318, to ground. While the connector switch is being elevated under the control of the high speed up-drive magnet, and as the brush 318 encounters a conducting segment of the commutator 317, the stepping relay 308 is short-circuited in the well-known manner.

It will be remembered that sequence switch 400 is in the same position as when it actuated a chain of counting relays in the brush selection of the finder switch. In this instance also, the same counting relay 120 is actuated to select a brush at the connector corresponding to the brush tripped by the finder. When the chain of counting relays has been actuated and the upper zero counting relay 409 is energized, the line relay 305 125 will deenergize and thereby complete a circuit from grounded battery, magnet of sequence switch 300, contact 319, back contact and right-hand armature of relay 305, to ground, to move this sequence switch out of 130

position 2 and into position 3. When the lower zero counting relay 427 is energized, a circuit is completed from ground, armature and front contact of relay 427, conductor 428, contact 429, conductor 430, contact 255, conductors 212, 211, right-hand armature and back contact of relay 201, contact 223, conductor 209, magnet of sequence switch 200, to ground, to move this sequence switch out of position 6.

In position 7 of the sequence switch 200, a circuit is established from grounded battery, winding of relay 202, conductor 256, contacts 257, 258, back contact and right-hand armature of relay 224, to ground. The line relay 202 attracts its armatures and at its left-hand armature and front contact completes a circuit from ground over conductor 234, contact 235, conductor 236, magnet of the sequence switch 200, to grounded battery, to move this sequence switch out of position 7 and into position 8.

While the sequence switch is rotating through position 7 and while it is resting 25 in position 8, an operating circuit is completed from grounded battery, winding of brush trip magnet 296, conductor 297, contact 298, to ground. This magnet 296 operates to trip the selected brush of the finder.

In position 8 of the sequence switch 200, a circuit for the low-speed up-drive magnet is established from grounded battery, winding of magnet 263, conductor 264, contact 265, conductor 234, left-hand front contact 35 and armature of relay 202, to ground. At this time the test relay 224 is connected to the test brush 266 over a path extending from grounded battery, right-hand winding of test relay 224, contacts 267, 268, conductor 40 269, to the test brush 266 of the finder switch. As the brushes of the finder switch are elevated the test brush 266 will engage the terminals of the lines in the selected group, until it encounters a grounded test 45 terminal. The test relay 224 will thereupon be energized and attract its armatures, and at its left-hand armature a circuit is completed from grounded battery, left-hand armature and front contact of relay 224, 50 low resistance winding of relay 224, conductor 269, test brush 266, test terminal and test conductor 270 of the calling line, left-hand winding of relay 105, right-hand front contact and armature of relay 109, to ground. The relay 105 attracts its armatures, and at its right-hand armature and back contact interrupts the energizing circuit of the line relay 104, to render this line 55 non-calling to other finders.

When the test relay 224 became energized, it interrupted the primary circuit of the line relay 202, and this relay will only remain energized until the brushes of the switch are accurately centered on the line 65 terminal, at which time the circuit com-

pleted through commutator brush 263 and the conducting segments of commutator 262, is interrupted by the brush 263 encountering an insulated segment of the commutator. Relay 202 at its left armature and contact 70 opens the circuit of driving magnet 263 and completes a circuit from grounded battery, magnet of sequence switch 200, conductor 236, conductor 209, contact 249, conductor 203, back contact and left-hand armature of relay 202, to ground, to move the sequence switch 201 out of position 8. The sequence switch 200 continues to rotate under the control of its master contact until it reaches position 11. When the line relay 104 is so deenergized and the test relay 224 is energized, the two sides of the differential circuit through the differential relay 107 will be opened, and if no other line in the particular group is calling, the relay 107 will 85 remain deenergized.

As the brushes of the finder are being elevated to test the successive lines in the various subgroups for the calling line, the commutator brush 243 will encounter an insulated segment of commutator 271 for each subgroup tested by the finder. As the commutator brush 243 encounters a conducting segment of the commutator 271, a circuit will be completed to actuate one of a chain 95 of counting relays. This circuit may be traced from ground, commutator brush 243, conducting portion of commutator 271, conductor 285, contacts 292 and 293, conductor 234', contact 437, conductor 438, armature 100 and back contact of counting relay 439, winding of counting relay 440, conductor 419, to grounded battery. The counting relay 440 is energized and attracts its armature. The relay 439, however, is short-circuited and will not be energized until the commutator brush 243 encounters an insulated segment on the commutator 271, in which case the energizing circuit for the relay 439 extends from grounded battery, 105 conductor 419, winding of relay 440, front contact and armature of this relay, winding of relay 439, conductor 441, contact 442, conductor 443, contact 295 to ground. The relay 439 attracts its armature and under 110 the control of the commutator brush 243, this pair of counting relays is actuated. Similarly other pairs of counting relays, as 444 and 445, are actuated for each subgroup 115 tested by the finder.

As the sequence switch 200 passes from position 9 to position 11, the relay 201 is connected to the talking conductor 299 over a circuit extending from ground, armature and back contact of relay 202, conductors 125 203 and 204, contact 205 winding of relay 201, conductor 206, contact 299', to the talking conductor 299. If the intercepted call originated over a final switch, trunk closure will have been completed and relay 201 will 130

be energized over conductor 299 through the finder and incoming switches, so that when sequence switch 200 reaches position 11, the relay 201 will be energized. However, if the 5 intercepted call originated over an incoming switch, then this incoming switch will have its sequence switch in the position of selection at the final switch and the relay 201 will not energize, since the conductor 299 10 will be connected to ground at the incoming switch. If the relay 201 is not energized in position 11, a sender restoring interrupter 298' will be connected to the talking conductor 297' over contact 294', contact 296', 15 back contact and armature of relay 201, contact 295' to the talking conductor 297', to return the sender connected with the mechanism which originated the call to its normal 20 position.

20 When the sequence switch 200 reaches position 11, the fundamental circuit is again closed through the circuit of the connector switch 301, as previously described. Line relay 305 will again energize and complete 25 a circuit from grounded battery, magnet of sequence switch 300, contact 309, right-hand front contact and armature of relay 305 to ground, to move this sequence switch out of position 3 and into position 4. In position 30 4 an operating circuit for the up-drive magnet is established from grounded battery, winding of magnet 310, contact 311, contact 312, conductor 314, right-hand front contact and armature of line relay 305, to 35 ground. As the brushes of the connector pass over each successive group of lines, the interrupter 320 closes a circuit in shunt of the fundamental circuit which may be traced from grounded battery, winding of line 40 relay 305, left-hand front contact and armature of this relay, contact 308, conductor 315, contact 321, commutator 320, commutator brush 318, to ground. This shunt circuit operates in the well-known manner to short- 45 circuit the stepping relay 408 so that for each group of ten lines passed by the switch, the stepping relay opens and closes the fundamental circuit.

It will be noted that there are eleven 50 counting relays in the chain, and that a number of these were energized by means of the interrupter 271 when the finder was hunting for the calling line. The sequence switch 201, in moving from position 8 to position 11, does not remove plus battery from 55 the counting relays actuated during the subgroup selection so that these relays still remain energized when the fundamental circuit is extended to the connector. Consequently, the energization of the additional counting relays by the shunting action occurring at the connector switch continues until the fundamental circuit is interrupted at the armature and back contact of the up- 60 per zero counting relay 409.

It will be seen that the number of counting relays actuated by the connector switch is the complement of the number of counting relays actuated by the finder when hunting for the line, so that if the lowest level 70 of the finder is seized, in which case but one pair of counting relays would be actuated, the connector switch would be actuated to its highest level, since the connector switch would continue to be actuated until the remaining ten counting relays are actuated. When the fundamental circuit is interrupted at the upper zero counting relay, and the brushes are centered, the line relay 305 is deenergized. This completes a circuit to 75 move the sequence switch 300 out of position 4 and into position 5. This circuit extends from grounded battery, magnet of sequence switch 300, contact 319, right-hand back contact and armature of relay 305, to 80 ground.

At the finder the relay 201 will be energized if the call originated over a final switch, and the incoming line will be in position for trunk closure. When the selection 90 at the connector is completed and the lower zero counting relay 427 is energized, a circuit is completed for moving the sequence switch 200 out of position 11 and into position 14, which circuit extends from ground, 95 armature and front contact of relay 427, conductor 428, contact 429, conductor 430, contact 255, conductors 212 and 211, right-hand armature and front contact of relay 201, contact 210, conductor 209, magnet of 100 sequence switch 200 to grounded battery. As the sequence switch 200 leaves position 12 it opens a circuit through the busy relay 428 at the contact 248. This releases the sender which has been used and allows it to 105 test idle to other finders.

As the fundamental circuit is opened after the selection in the tens subgroup at the switch and the sequence switch 300 is moved into position 5, a circuit will be completed from grounded battery, left-hand winding of the test relay 322, contact 323, to ground. The test relay 322 attracts its armatures and at its left-hand armature completes a circuit from ground through conductor 324, contact 325, contacts 312 and 309, magnet of sequence switch 300, to 115 grounded battery. This circuit operates to move the sequence switch out of position 5 into position 6.

In position 6 of this sequence switch an operating circuit is completed from grounded battery through the winding of low-speed up-drive magnet 326, contact 327, contact 325, conductor 324, left-hand front contact and armature of test relay 322, to ground. The test relay 322 will remain energized after the sequence switch 300 is moved out of position 5, over a circuit extending from grounded battery, right-hand 120 125 130

winding of relay 322, right-hand front contact and armature of this relay, conductor 328, test brush 329 over busy test terminals. The test terminals of busy lines are connected to ground. In case of idle lines, this ground is not connected to the test terminal. When, therefore, the test brush 329 encounters an idle test terminal such as 330, the test relay 322 will deenergize and in so doing 10 will complete a circuit to move the sequence switch 300 out of position 6. This circuit may be traced from grounded battery, magnet of sequence switch 300, conductor 331, contact 332, contact 333, left-hand back contact and armature of test relay 322, to ground. As soon as the sequence switch 300 leaves position 6, the operating circuit for the up-drive magnet is interrupted at contact 327. In position 7 of the sequence switch 300, the 15 connector awaits trunk closure at the finder switch.

When sequence switch 300 of the connector has reached position 7, a circuit is completed to energize the relay 334. This circuit extends from grounded battery, contact 335, relay 334, conductor 253, contact 252, contact 293', conductor 272, contacts 434 and 431, to ground. The relay 334 is energized and attracts its armature to complete a circuit from ground, armature and front contact of relay 334, contact 336, contact 304, winding of line relay 305, to grounded battery. Line relay 305 attracts its armatures and at its left-hand armature 25 and front contact completes a locking circuit for itself through contact 308 over the circuit previously described. At the right-hand armature and front contact of relay 305, a circuit is completed from ground battery, contact 309, magnet of sequence switch 300 to ground battery to move the sequence switch out of position 7 and into position 8. When the sequence switch 300 is rotated 30 through position 7₁, a circuit is completed 40 from grounded battery, winding of relay 305, left-hand front contact and armature of this relay, contact 308, contact 337, conductor 254, conductor 273, contact 250, contact 214, winding of relay 201, contact 274, to ground. Line relay 305 will therefore 45 remain energized as long as the finder sequence switch 200 remains in position 14. The relay 201 is energized and at its left-hand front contact and armature closes a circuit to move the sequence switch 200 out of position 14 and into position 15. This circuit may be traced from grounded battery, magnet of sequence switch 200, conductor 236, conductor 209, contact 210, 50 right-hand front contact and armature of the relay 201, conductor 211, conductor 212, contact 213, to ground. When the sequence switch 200 leaves position 14 the energizing circuit for the line relay 305 is opened, 55 and this relay at its right-hand back con-

tact and armature completes a circuit from grounded battery, magnet of sequence switch 300, contact 319, to ground, to move the sequence switch 300 out of position 8 and into position 16. 70

When sequence switch 200 moved into position 15, a circuit was completed to move this sequence switch out of position 15 into position 16, which circuit extends from grounded battery, magnet of sequence switch 200, conductors 236, 209, contact 223, conductors 211, 212, contact 213, to ground. 75

Sequence switch 200, in passing through positions 12 to 15, closes a circuit through battery, ringing trip resistance 275 over the 80 talking conductor 297' back to the incoming switch, so that the ringing relay (not shown) at the incoming switch will be tripped.

When the sequence switch 200 is in positions 15 to 1, a circuit is completed for the sequence switch 400 to move this sequence switch to the test position of the next finder. This circuit may be traced from grounded battery, magnet of sequence switch 400, contact 432, conductor 433, contact 277, to ground. 85

As soon as the connector sequence switch 300 reaches position 16, a circuit is completed from the grounded battery, repeating coil 342, supervisory relay 343, contact 344, conductor 345, brush 346, terminal and conductors 347, and 348, winding of relay 349, back contact and armature of relay 350, test terminal 330, brush 329, conductor 328, contact 352 to ground. Relay 349 attracts its armature and thereby completes a circuit from ground, its armature and contact, lamp 353, relay 354, to grounded battery. Lamp 353 remains lighted until the operator inserts the answering plug, the sleeve of which is connected to grounded battery, whereupon relay 350 will be energized through the sleeve of jack 355, conductor 356, winding of relay 350 to ground. Relay 350 attracts 100 its armature and thereby establishes a locking circuit for itself through test terminal 330, test brush 329, conductor 328, contact 352 to ground. The locking circuit through relay 350 is provided to prevent the lamp 105 353 relighting for the same call when the operator removes the answering plug.

The calling substation is now connected to the intercepting operator's position, at which time a circuit is completed for the supervisory relay 343. When the intercepting operator has given the desired information and disconnection has taken place over switches indicated by the brushes 101, 102 and 103, the energizing circuit of relay 109 120 is interrupted, causing this relay to retract its armatures. At the right-hand armature of this relay grounded battery is connected to the left-hand winding of relay 106. When ground is disconnected from the right- 125 130

- hand winding of relay 105, the locking circuit of the test relay 224 is interrupted, causing this relay 224 to deenergize. At the right-hand armature and back contact of relay 224, a circuit is established from ground, contacts 258 and 278, test brush 266, terminal and test conductor 270, left-hand winding of relay 105, back contact and right-hand armature of relay 109 to grounded battery.
- 5 The relay 105 maintains its armatures attracted and at its right-hand armature and back contact opens a break point in the conductor leading to the line relay 104, to prevent reenergization of this relay. When the test relay 224 deenergized, a circuit was established from grounded battery, left-hand armature and back contact, resistance 225, contact 279, conductor 206, winding of relay 201, contact 205, conductor 203, left-hand 15 back contact and armature of relay 202, to ground. The relay 201 attracts its armatures and thereby completes a circuit to move the sequence switch 200, out of position 16. This circuit may be traced from grounded battery, magnet of sequence switch 200, conductors 236 and 209, contact 210, right-hand front contact and armature of relay 201, conductors 211 and 212, contact 213 to ground.
- 20 In position 17 of the sequence switch 200, an operating circuit for the downdrive magnet 280 is completed from grounded battery, winding of this magnet, contacts 281 and 213 to ground. The finder under the control of this magnet is restored to normal position. As soon as the finder switch reaches its normal position, a circuit is completed to move the sequence switch 200 out of position 17 into position 18, in which position it 25 remains awaiting allotment. This circuit may be traced from ground, brush 243, a normal contact 282, conductor 283, contact 284, conductors 209 and 236, magnet of sequence switch 200, to grounded battery.
- 30 As the sequence switch moved out of position 16 it interrupted at its contact 252 the energizing circuit for the relay 334, which relay was energized during conversation. When the relay 334 retracts its armature it 35 opens the energizing circuit of the line relay 305. The relay 305 retracts its armatures, and at its right-hand armature and back contact completes a circuit from ground through contact 319, magnet of sequence switch 300, to grounded battery, to move this sequence switch out of position 16 into position 18. In position 18 an operating circuit for the down-drive magnet 257 is completed from grounded battery, winding of magnet 357, contact 358, to ground. The down-drive magnet restores the connector switch to its normal position. When this normal position is reached a circuit is closed from ground through commutator brush 318, 40 normal contact 359, conductor 360, contact

361, magnet of sequence switch 300, to grounded battery. This circuit causes the sequence switch 300 to move out of position 18 into position 1.

If at any time one of the differential relays similar to 107 becomes energized long enough to energize one of the relays 201, and this relay does not remain energized until the sequence switch 400 has accomplished its testing of the group; the sequence switch 400 will rotate until it reaches its next test position, that is, in one of the positions 1, 7 or 13. However, in passing from one test position to the next test position, the holding circuit of the relay 201 will be momentarily opened, so that the magnet of sequence switch 200 will be energized over a circuit previously described. When the sequence switch 200 reaches position 3, the fundamental circuit to the sender will be opened at the contacts 407 and 411, and an operating circuit for advancing the sequence switch 200 to position 4 will be established from grounded battery, magnet of sequence switch 200, conductors 236 and 209, contact 223, right-hand back contact and armature of relay 201, conductor 211, contacts 436 and 451, to ground. In position 4 of the sequence switch 200 the line relay 202 is still deenergized, and at its left-hand armature and back contact completes a circuit from ground through conductor 203, contact 249, conductors 209 and 236, magnet of sequence switch 200 to grounded battery, to move the sequence switch into position 6. Since the brushes of the finder have not been elevated, the commutator brush 243 will be in engagement with its normal contact 282. A circuit is completed for moving the sequence switch 200 out of position 6 and into position 18. This circuit may be traced from grounded battery, magnet of sequence switch 200, conductors 236 and 209, contact 284, conductor 283, normal contact 282, commutator brush 243 to ground. Similarly, if the sequence switch 200 is moved out of position 1 for any reason except the regular operation of the switch, sequence switch 200 will continue to rotate as above described back to position 18.

When sequence switch 200 is rotated through its various positions due to abnormal conditions as explained above, the closure of its various contacts will not affect any sender, since under these conditions the sequence switch 400 is standing in one of its test positions 1, 7 or 13, in which positions the various circuits of the sender are open. Also, any abnormal operation of the sequence switch 200 will not affect the circuit of the connector switch governed by the sequence switch 300, since the fundamental circuit will always remain open at the contacts of sequence switch 400 in one of its testing positions.

If, due to any trouble in the circuits, as for example, poor contacts in the sender circuit, brush selection is not properly governed, then the brushes of the finder switch 5 will be elevated to their highest position, thereby closing the overflow contact 286. As soon as contact 286 is closed in positions 10 to 8 of sequence switch 200, the test relay 224 is immediately energized over contact 267. This opens the circuit to the differential relay 107 at the armature and back contact of relay 224 so that the calling line can immediately start another finder. When 15 the relay 224 is energized in position 4 of the sequence switch 200, it closes an operating circuit to advance this sequence switch into position 6. This circuit may be traced from ground, right-hand armature and front contact of relay 224, contacts 287 and 278, 20 contact 249, conductors 209 and 236, magnet of sequence switch 200 to grounded battery. In position 6 of this sequence switch, the relay 224 is maintained energized and a circuit will be closed over the right-hand front 25 contact and armature of relay 224, conductor 288, contact 289, to the tell-tale signal 290.

If the cause of any improper action of the connector switch is due to a poor contact in 30 the sender circuit, the brushes of the connector switch will be advanced to their highest position, thereby closing a circuit to the overflow contact 398. With overflow contact 398 closed, a circuit is completed through 35 the contact 332 to rotate the sequence switch 300 to position 7, or to the position in which trunk closure is awaited. Sequence switch 300 in position 7 closes a circuit from ground through commutator brush 318, contact 398, 40 conductor 362, contact 399, which leads to the tell-tale signal. In the last mentioned case the sequence switch 200 will be held in position 6, the sequence switch 300 will be held in position 7, and the sender will remain on the line, so that the cause of the trouble can be found and investigated. In case the trouble occurs while the finder is hunting for the calling line, that is, while 45 the sequence switch 200 is in position 8, the closure of contact 286 will immediately open the differential circuits to the relay 107. The energization of relay 224 will open the energizing circuits of relay 202, causing this 50 relay to retract its armatures. At the left-hand armature and back contact of relay 202, a circuit is closed to move the sequence switch 200 from position 8 into position 11. In position 11, with the overflow contact 286 closed, the relay 202 will be energized and 55 will close the circuit from ground, left-hand armature and front contact of relay 202, conductor 234, contact 291, to the tell-tale signal 211.

What is claimed is:

65 1. In a telephone system, groups of in-

coming lines, groups of outgoing lines, means including automatic switches for interconnecting any incoming line with any outgoing line, and means controlling the setting of one of said switches in operative 70 relation to a group of incoming lines and for subsequently controlling the setting of a second automatic switch in operative relation to a corresponding group of outgoing lines.

2. In a telephone system, groups of incoming lines, groups of outgoing lines, means including automatic switches for interconnecting any incoming line with any outgoing line, and a counting device for controlling the setting of one of said switches 75 in operative relation to a group of incoming lines, and for controlling the setting of a second automatic switch in operative relation to a corresponding group of outgoing lines.

3. In a telephone system, groups of incoming lines, groups of outgoing lines, means including automatic switches for interconnecting any incoming line with any outgoing line, and means controlled by the 90 setting of one of said automatic switches in operative relation to a group of incoming lines to subsequently govern the setting of a second automatic switch in operative relation to a corresponding group of outgoing 95 lines.

4. In a telephone system, groups of calling lines, an outgoing line, means including an automatic switch for interconnecting any calling line with said outgoing line, and means including a counting device for controlling the setting of said automatic switch in operative relation to a group of calling lines.

5. In a telephone system, groups of calling lines, an outgoing line, means including an automatic switch for interconnecting any calling line with said outgoing line, and means including a counting device controlled by the condition of said groups of 105 calling lines for determining the setting of said automatic switch in operative relation to a group of calling lines.

6. In a telephone system, groups of incoming lines, groups of outgoing lines, 115 means including automatic switches for interconnecting any incoming line with any outgoing line, and a counting device actuated in a certain manner by the group selection of one of said switches, said counting device when actuated in a complementary manner operating to control the setting of a second automatic switch in operative relation to a corresponding group of outgoing lines.

7. In a telephone system, a group of incoming lines, a group of outgoing lines, means including automatic switches for interconnecting any incoming line with any outgoing line, and a counting device actu-

ated by one of said automatic switches while 5 locating the calling line, said counting device when actuated in a complementary manner controlling the setting of a second automatic switch in operative relation to one of said groups of outgoing lines.

8. In a telephone system, groups of calling lines, an outgoing line, means including an automatic switch for interconnecting any 10 calling line with said outgoing lines, a plurality of counting devices, any one of which operates to control the setting of said automatic switch in operative relation to a group of calling lines, and means for allotting one 15 of said counting devices for use.

9. In a telephone system, groups of incoming lines, groups of outgoing lines, means including automatic switches for interconnecting any incoming line with any 20 outgoing line, a plurality of counting devices, each of said counting devices being arranged to be actuated by one of said automatic switches while locating the calling line, and to be actuated in a complementary 25 manner to control the setting of a second automatic switch in operative relation to one of said groups of outgoing lines, and means for allotting a counting device for use.

30 10. In a telephone system, a link circuit provided at each end with an automatic switch, incoming lines terminating at one of said switches and arranged in groups and sub-groups at said switch, outgoing lines 35 terminating at the other switch and arranged in groups and sub-groups thereat, and a counting device operating to set each of said switches in operative relation to corresponding groups of lines at each of said 40 switches and subsequently to control the setting of one of said switches in operative relation to sub-groups corresponding to the sub-group selection at the other switch.

11. In a telephone system, a link circuit 45 provided at each end with an automatic switch, incoming lines terminating at one of said switches and arranged in groups and sub-groups thereat, outgoing lines terminating at the other automatic switch and arranged in groups and sub-groups thereat, 50 and means operating to control group selection at each of said switches, said means being also actuated by the sub-group selection at one of said switches to control the sub-group selection at the other automatic 55 switch.

12. In a telephone system, a link circuit provided at each end with an automatic switch, incoming lines terminating at one of said switches and arranged in groups 60 and sub-groups thereat, outgoing lines terminating in the other automatic switch and arranged in groups and sub-groups thereat, and a counting device operating to control group selection at each of said switches, said 65 counting device being also actuated by the sub-group selection at one of said switches to control the sub-group selection at the other automatic switch.

13. In a telephone system, a link circuit 70 provided at each end with an automatic switch, incoming lines terminating at one of said switches and arranged in groups and sub-groups thereat, outgoing lines terminating at the other automatic switch and arranged in groups and sub-groups thereat, 75 and a counting device operating to control group selection at each of said switches, said counting device being set in accordance with the sub-group selection at one of said 80 switches to control the sub-group selection at the other switch.

In witness whereof, I hereunto subscribe my name this 26th day of December, A. D. 1916.

WILLIAM H. MATTHIES.
